United States Patent Office

Des. 210,217

Patented Feb. 20, 1968

210,217

CARD READER IMPRINTER

James Russell Williams, Camp Hill, Pa., assignor to AMP
Incorporated, Harrisburg, Pa.

Filed Oct. 24, 1966, Ser. No. 4,383

Term of patent 14 years

(Cl. D26—5)

I claim:

The ornamental design for a card reader imprinter, substantially as shown.
